UNITED STATES PATENT OFFICE.

MARY F. BISHOP, OF PHILADELPHIA, PENNSYLVANIA.

DESIGN FOR A MOISTENER FOR AN ENVELOP, POSTAGE-STAMP, OR SIMILAR ARTICLE.

51,436.

Specification for Design.

Patented Oct. 30, 1917.

Application filed August 31, 1917. Serial No. 189,227. Term of patent 14 years.

To all whom it may concern:

Be it known that I, MARY F. BISHOP, a citizen of the United States, residing at Philadelphia, county of Philadelphia, and State of Pennsylvania, have invented a new, original, and ornamental Design for a Moistener for an Envelop, Postage-Stamp, or Similar Article, of which the following is a specification, reference being had to the accompanying drawing, forming part thereof.

The Figures 1 and 2 of the drawing are respectively a side elevation and a plan

view of a moistener for an envelop, postage stamp or similar article, showing my new design.

I claim:

The ornamental design for a moistener for an envelop, postage stamp, or similar article, as shown.

In testimony whereof I affix my signature in presence of two witnesses.

MARY F. BISHOP.

Witnesses:

S. M. CLARKE,
HENRY H. WIECHERS.
